COLLAPSIBLE DISPENSING TUBE

Albert John Van Scyoc, Orange, N. J.

Application May 12, 1939, Serial No. 273,184

2 Claims. (Cl. 221—60)

This invention relates to collapsible dispensing tubes and more especially to closures for such tubes.

An object of this invention is a closure structure which includes a cap adapted when screwed on tightly to seal the tube and when rotated approximately a quarter turn from such sealing position to open a passage through which the contents of the tube may be discharged.

According to this invention the collapsible tube is provided with an externally threaded neck or spout having a substantially diametrically arranged barrier extending across its outer end and forming two apertures the area of each of which is less than one-half the cross section of the discharge spout. A cap is threaded onto said neck and is provided with a diametrically arranged slot which is adapted when the cap is screwed down tightly to register with the barrier and seal the tube. However, when the cap is turned back a quarter turn it brings the slot into register with the two apertures thus providing a discharge passage. Initially a sealing disk is provided in the cap and closes the slot therein and also limits the extent that the cap can be screwed onto the neck. The user first unscrews the cap from the neck, extracts the sealing disk, and then screws the cap back onto the neck, thus making it ready for use as above described.

Other objects, novel features and advantages of this invention will be apparent from the following specification and accompanying drawing wherein:

Figure 1 is an exploded view of a collapsible tube closure embodying the invention.

Figure 2 is a side elevation, partially broken away, showing the sealing disk in place.

Figure 3 is an end view with the sealing disk removed and the cap screwed down tightly.

Figure 4 is a section on the line 4—4 of Fig. 3.

Figure 5 is a view similar to Fig. 3 with the cap rotated a quarter turn.

Figure 6 is a section on the line 6—6 of Fig. 5.

In the drawing a collapsible tube 10 of standard construction is provided with an exteriorly threaded neck 11 at the outer end of which is provided a substantially diametrically arranged barrier 12 at either side of which is provided an aperture 13. An interiorly threaded cap 14 screws onto the neck 11 and is provided with a diametrically arranged slot 15. A sealing disk 16 is initially placed in the cap 14 to engage the end of the neck 11 to seal the tube until such time as it is desired to make use of its contents. Such sealing disk is shown in Fig. 1 and also in Fig. 2

55 the disk is shown in its sealing position. The

thickness of the disk 16 limits the extent to which the cap 14 can be screwed down on the neck 11.

When it is desired to make use of the contents of the tube the cap 14 is removed from the neck by unscrewing it in the usual manner and the sealing disk is extracted. The cap is then replaced and screwed down into the position shown in Fig. 4 in which the slot 16 registers with the barrier 12 to prevent discharge of the tube contents. Rotation of the cap 15 through a quarter degree turn brings the slot 16 crosswise of the barrier 12 as shown in Figs. 5 and 6, thus putting the apertures 13 into communication with the slot 16. The contents of the tube 10 may now be discharged through a passageway thus provided by collapsing the tube in the usual manner.

After as much as desired of the contents has been discharged, the cap 14 is screwed down on the neck 11 as far as it will go thereby bringing the slot 16 again into registry with the barrier 12 and sealing the tube.

While the preferred embodiment of the invention is as has been above described, it is to be understood that other modifications are contemplated. However, in such modifications the neck or spout will be equipped with a barrier arranged flush with the end of the neck or spout to partially close the same and the cap will be provided with an aperture or slot which registers with the barrier when the cap is screwed down tightly thereby sealing the tube and which communicates with the open portion of the neck or spout when unscrewed slightly, thereby providing a dispensing passageway.

I claim:

1. In combination, a collapsible dispensing tube having an exteriorly threaded discharge spout with a diametrically arranged barrier extending across its end and forming two apertures, and an interiorly threaded cap on said spout, said cap having a diametrically arranged slot adapted in one position of said cap on said spout to align with said barrier and in another position to be in communication with said apertures.

2. In combination, a collapsible dispensing tube having an exteriorly threaded discharge spout with a diametrically arranged barrier extending across its end and forming two apertures, and an interiorly threaded cap on said spout, said cap having a diametrically arranged slot adapted, when said cap is screwed tightly onto said spout, to align with said barrier to seal said tube, and, when rotated a quarter turn from such position, to communicate with said apertures.
